(57) **CLAIM**

The ornamental design for a LED light, as shown and described.

DESCRIPTION

FIG. 1 is a front perspective view of a LED light, showing my new design;

FIG. 2 is a front view of the LED light;

FIG. 3 is a rear view of the LED light;

FIG. 4 is a first side view of the LED light;

FIG. 5 is a second side view of the LED light;

FIG. 6 is a third side view of the LED light;

FIG. 7 is a fourth side view of the LED light; and,

FIG. 8 is a perspective view of the LED light shown in an environment of use in a mounted configuration.

The broken lines in the drawings illustrate portions of the LED light that form no part of the claimed design. The additional broken lines shown in FIG. 8 depict environmental subject matter only, which forms no part of the claimed design.
